(57) **CLAIM**

The ornamental design for a wheelchair, as shown and described.

DESCRIPTION

FIG. 1 is a perspective view of a wheelchair showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged fragmentary perspective view showing a control device of the wheelchair;

FIG. 9 is a front elevational view showing the control device;

FIG. 10 is an enlarged fragmentary perspective view showing a pedal device of the wheelchair;

FIG. 11 is another enlarged fragmentary perspective view showing the pedal device;

FIG. 12 is a fragmentary front elevational view showing the pedal device;

FIG. 13 is a fragmentary rear elevational view showing the pedal device;

FIG. 14 is a fragmentary right side elevational view showing the pedal device; and,

FIG. 15 is a fragmentary top plan view showing the pedal device.

The broken line showing forms no part of the claimed design.
